ELECTRICAL CONTACT CONTROL DEVICE

Robert J. Little, Gates, N. Y., assignor to General Railway Signal Company, Rochester, N. Y.

Application June 21, 1940, Serial No. 341,701

4 Claims. (Cl. 200—87)

This invention relates, in general, to contact control devices, and has more particular reference to a quick acting or snap action contact controlling means of particular value for use in connection with railway operation.

In opening and closing electric circuits, and particularly direct current circuits, it is desirable to make and break the circuits rapidly in order to minimize as much as possible the resulting wear and burning of contacts due to the formation of arcs.

With the above and other objects in view, it is proposed, in accordance with this invention, to provide a quick acting means for making and breaking circuits, the quick acting means employing permanent magnets for producing a snap action effect, whereby to avoid undue friction and wear of parts as occurs in connection with spring and elastic means ordinarily employed in this connection.

More specifically, it is proposed to open and close circuit contacts by driving an operating member carrying a magnet which cooperates with another magnet carried by an operated member, with the magnet so arranged as to exert a strong bias on the members involved.

Further objects, purposes and characteristic features will appear as the description progresses, reference being made to the accompanying drawing, showing, solely by way of example, and in no manner whatsoever in a limiting sense, several forms which the invention can assume. In the drawing:

Fig. 1 is a schematic view of one form of the invention, shown in one of its operated positions.

Fig. 2 is a schematic view of the same form of invention as that shown in Fig. 1, but with the parts in a different operated position.

Fig. 3 is a schematic view of a second form of the invention, with the parts shown in one operated position.

Fig. 4 is a schematic view of the same form of invention as shown in Fig. 3, but with the parts shown in a different operated position.

Fig. 5 is a schematic view of a third form of the invention.

Fig. 6 is a schematic view of the fourth form of the invention.

Referring now to the drawing, and first to Figs. 1 and 2, there is here shown a contact controlling device involving a top plate or support TP, to which are connected movable contact fingers 1 and 2, carrying contact points 3 and 4, for cooperating with fixed contact fingers 5 and 6, and 7 and 8, respectively. These fixed contact

10 fingers respectively have contact joints 9 and 10, and 11 and 12, as shown in the drawing. The contact fingers can be connected to the top plate in any usual or desired manner, one suitable form being shown in the drawing whereby each contact finger, such as 5, is clamped to the top plate by a through bolt 13 and nut 14, with an angle bracket 15 on the underside of the top plate for holding the bolt head 16 against accidental turning. Wire connections can conveniently be made to the upper end of the bolt 13.

15 The contacts, if desired, instead of merely being pressed against each other, by the magnetic repulsion, can be of the spring slip type, wherein a blade is held between two spring members so as to require considerable force to withdraw the blade.

20 The lower ends of the movable contact fingers 1 and 2 are connected in any suitable manner, as at 16¹, to a carrier, or operated member, C, whereby to move with the carrier. This carrier is made of any suitable insulating material.

25 For actuating the carrier, the armature, or operating member, A, is employed, which, as shown in the drawing, is pivoted at 17 to a bracket B, connected in any suitable manner to the top plate. The armature A has a slot 18 therein, for receiving an eccentric 19, rotating on a center 20 whereby to shift the armature from one side to the other of a pivot 17, to assume the extreme positions shown, respectively, in Figs. 1 and 2. This eccentric 19 can be driven in any desired manner, as for example, by a constant speed motor such as disclosed in application Ser. No. 198,928, filed 30 March 30, 1938 in the name of O. S. Field which application became Patent No. 2,206,667 on July 2, 1940.

35 Carried by the lower end of armature A is an armature magnet AM, which, in the present form, is shown in the shape of a horseshoe with its poles N and S extending downwardly. This magnet is of the permanent type and is preferably very strong for its size and can be made of some suitable alloy such as "Alnico." This material has a very high retentivity and retains its magnetism to a strong degree so as to require a very high coercive force to destroy the magnetism.

40 Supported by the carrier C, is a carrier magnet CM, of a shape like magnet AM, and facing with its pole shoes towards the pole shoes of the armature magnet AM. This carrier magnet CM is preferably made of the same material, "Alnico," as the armature magnet and has its poles so arranged as to have like poles opposed to the poles

of the armature magnet, when the armature A is in an intermediate operated position.

It can be seen, with the armature and carrier magnets opposed as described above, that when the armature A is swung from the position shown in Fig. 1, toward the position shown in Fig. 2, to ultimately reach the position indicated in Fig. 1 by the dotted "N" pole 21, the like poles repel each other, and so continue to until these like poles are directly opposed to each other, whereupon added movement of the armature causes the repulsion to operate in the reverse direction, on the carrier magnet, and quickly move the carrier C to its right hand position as shown in Fig. 2 whereby to make up fixed contacts 6 and 8, and break the contacts 5 and 7 which are made in Fig. 1.

In Fig. 2, in dotted lines, is shown the extreme right-hand position of the south pole "S," identified as 22, whereby it can be seen, upon armature A being moved to the right, that the contact pressure between contacts 4 and 12, for example, is increased as the armature approaches the position where its magnet is over the carrier magnet. Upon the two magnets becoming directly opposed, the parts are not biased to either extreme position but upon the slightest further movement of the armature the bias of repulsion of the magnets is exerted on the carrier to quickly move it to the left-hand position, as shown in Fig. 1.

With the structure as described above, it follows that, with the eccentric 19 driven continuously in one direction, the armature oscillates from one side to the other of the center line of the structure, and makes up the different contacts with a very quick snap action and in so doing produces no friction or rubbing of parts, as usually occurs in snap action switches.

Referring now to Figs. 3 and 4, a fragmentary showing of a modified form of the invention is involved wherein the armature A¹ can be operated as in the above described form of invention, and the contact carrier C¹ can carry contacts, as described above. The difference in this form of invention involves positioning the permanent magnets so that only one pole of each magnet cooperates in the operation. For example, the bar magnets 23 and 24, carried respectively by the armature and carrier, have their north poles adjacent and opposed, and hence exert a repulsion toward either of the two extreme operated positions of the carrier. As in the form described above, as the armature swings from right to left, as shown in Figs. 3 and 4, the north poles N of the bar magnets become opposed, and upon the slightest further movement the carrier C¹ is moved with a snap action to the reverse position, to make up the reverse contacts.

In the form of invention of Figs. 3 and 4, it can be seen that the magnetic bias to extreme position continues regardless of how far the carrier moves, although of course, the biasing force decreases rapidly as the space between the magnets increases in accordance with well known principles of magnetic attraction and repulsion. With the cooperation of two poles on each magnet, as in the form of Figs. 1 and 2, it can be seen that the bias would cease if the armature could swing far enough beyond its extreme position to bring the south pole S, for example, of the armature magnet A, directly opposite the north pole N, of the carrier magnet C. This is no great disadvantage, however, so long as

the contacts and the structure be so arranged that the extreme position, as limited by the structure, is reached before this opposite pole opposition position is reached.

Referring now to Fig. 5 of the drawing there is here shown a slightly modified form of the invention, wherein the carrier C² and armature A², carried by arms 36 and 37 and pivoted as at 17, together with the permanent magnets 25 and 26, cooperate in substantially the same manner as described above. The carrier has contacts 27 and 28, which cooperate with fixed contacts 29 and 30, when moved to the extreme positions. The armature A², in this form of invention, is illustrated as being operated from one side to the other by an armature member 31 operating against adjustable stops 32 and 33 and actuated by electromagnetic means such, for example, as described in the patent to O. S. Field, 1,969,065, granted August 7, 1934. This structure referred to is employed to advantage in flashing signals at highway crossings on railways and the present snap action means disclosed can be used to advantage in such connections.

Referring to Fig. 6, there is here shown a further form of the invention wherein magnets 34 and 35 are carried, respectively, by the armature A³ and carrier C³, the magnets being of the horseshoe type and positioned at right angles to the plans of the members which carry them instead of in the same plan, as in the case with the forms of Figs. 1, 2 and 5. In this form, the like poles repel each other in the same manner as in the forms previously described, but the structure functions as does the form of Figs. 3 and 4, in that the repulsion of the two magnets continues regardless of the distance the carrier moves, although, of course, it diminishes with distance, as well understood by those versed in this art. It is seen that in this form both poles of each magnet is effective in producing repulsion rather than only one of each magnet, as in the form of Figs. 3 and 4.

In the above disclosure of several forms of this invention, it is desired to be understood that the contact arrangements illustrated are given merely by way of example, and various other arrangements of front and back contacts can be employed.

Furthermore, the actuating means disclosed are merely given by way of example and it is contemplated that the armatures can be operated either continuously or intermittently by any usual or desired drive means other than those disclosed above, as, for example, by thermal means, or by hand, or in any other desired manner.

The above disclosed invention supplies a snap action device, which is substantially freed from friction, and hence, one which greatly minimizes the usual wear of devices of this general type, and is very durable and dependable in its operation.

The above rather specific description of several forms of invention has been given solely by way of example, and is not intended, in any way whatsoever, in a limiting sense. Various modifications and alterations as may occur desirable from time to time, are contemplated as being covered by the present application, insofar as they are not specifically excluded therefrom by the appended claims.

Having described my invention I now claim:

1. In a contact operating means, an operator

75 a movable operated member, contacts operatively

associated with the operated member, means for moving the operator from one to the other of two extreme positions, a U-shaped magnet carried by the operated member, a U-shaped magnet carried by the operator and positioned to cause its poles to move in close opposition to, but out of contact with, the like poles of the carrier magnet when the operator is intermediate its extreme positions, whereby to repel the operated member toward one or the other of the two extreme positions when the operator is in the other, or the one, extreme position, the said U-shaped magnets having their poles all in the plane of movement of the said operator.

2. In a contact operating means, an operator, a movable operated member, contacts operatively associated with the operated member, means for moving the operator from one to the other of two extreme positions, a U-shaped magnet carried by the operated member, a U-shaped magnet carried by the operator and positioned to cause its poles to move in close opposition to, but out of contact with, the like poles of the operated member carried magnet when the operator is intermediate its extreme position, whereby to repel the operated member toward one, or the other, of the two extreme positions, with a snap action, when the operator is moved beyond its intermediate position toward the other, or the one, extreme position, and to bias the operated member to the extreme position by both magnetic attraction and repulsion, the said U-shaped magnets having their poles all in the plane of movement of the said operator.

3. In a contact operating means, an operator, a movable operated member, contacts operatively associated with the operated member, means for moving the operator from one to the other of two extreme positions, a U-shaped magnet carried by the operated member, a U-shaped mag-

net carried by the operator and positioned to cause its poles to move in close opposition to, but out of contact with, the like poles of the operated member carried magnet when the operator is intermediate its extreme positions, whereby to repel the operated member with a snap action toward one, or the other, of the two extreme positions, when the operator is, respectively, moved beyond its intermediate position toward said other, or said one, extreme position, the operator, when moving to either extreme position, thus moving these said poles of its magnet beyond opposition to said like poles of the operated member carried magnet, and means to restrain the operator from moving the poles of its magnet into opposition with opposite poles of the operated member carried magnet.

4. In a contact operating means, an operator, a movable operated member, a substantially frictionless pivot for the operated member comprising an elongated flexible strip fixed to the operated member at one end, and at its other end fixed to a stationary support, contacts operatively associated with the operated member, means for moving the operator from one to the other of two extreme positions, a U-shaped magnet carried by the operated member, a U-shaped magnet carried by the operator and positioned to cause its poles to move in close opposition to, but out of contact with, the like poles of the operated member magnet when the operator is intermediate its extreme positions, whereby to repel the operated member toward one or the other of the two extreme positions, when the operator is in the other, or the one, extreme position, the said U-shaped magnets having their poles all in the plane of movement of the said operator.

ROBERT J. LITTLE.
